UNITED STATES PATENT OFFICE.

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY.

CLOSE-CORNER DRILL.

1,255,316.

Specification of Letters Patent.

Patented Feb. 5, 1918.

Original application filed June 19, 1915, Serial No. 35,109. Divided and this application filed May 11, 1917. Serial No. 167,992.

To all whom it may concern:

Be it known that I, FRANCIS A. JIMERSON, a citizen of the United States, residing at Athens, in the county of Bradford and 5 State of Pennsylvania, have invented a certain new and useful Improvement in Close-Corner Drills, of which the following is a specification.

This invention relates to fluid operated 0 rotary drills, and more particularly to drills of this type known as "close corner drills", which are designed to operate in restricted spaces, and particularly relates to improvements in the type of drill shown in 15 the patent of Caid H. Peck, No. 1,172,901, granted February 22d, 1916, this application being a division of my co-pending application Serial No. 35,109 filed June 19th, 1915.

20 These drills, as usually constructed, consist of an elongated casing in the extremity of one end of which is located a rotary spindle which is generally operated by a series of ratchet levers driven through the 25 medium of small reciprocating motor elements set in the other end of the casing.

An object of the invention is to provide a 30 construction having the motor pistons engaging and actuating the ratchet levers without the interposition of intermediate elements in which means are provided to definitely control the respective positions of the ratchet levers with regard to each other and at the same time limit and control their 35 angular movement with respect to the drill spindle.

A further object is to provide an arrangement for the ratchet levers and their driving 40 motors whereby a plurality of motors and ratchet levers having equal power can be arranged in a restricted space.

With these, and other objects which will 45 further appear, in view, a drill has been devised, a practical embodiment of which is shown in the accompanying drawings, in which,

50 Figure 1 is a side view, partly in section, on the line 1—1 of Fig. 2, and partly broken away to show the ratchet levers and motor mechanism in side elevation,

Fig. 2 is a longitudinal horizontal section on the line 2—2 of Fig. 1, and Fig. 3 is a partial view of the casing, showing the bearing for the crank shaft in section.

The drill, as shown, comprises an elongated casing 1, at one extremity of which is a cylindrical spindle sleeve 2 the ends of which project above and below the casing 1. In this spindle sleeve 2 is rotatably supported the spindle 3, this spindle having an upper bearing portion 4, a central toothed portion 5 and a lower bearing portion 6, these being all of the same outer diameter. The bearing portion 6 is journaled in a bushing in the lower part of the sleeve 2, 65 while the bearing portion 4 is journaled in a bushing 7 which has an upper flange 8 resting on a shoulder in the sleeve 2. The spindle 3 is provided at its upper end with a flange 9 which rests on the upper face of the bushing 8, thus preventing movement of the spindle in a downward direction, while movement of the spindle in an upward direction is prevented by a cap 10 threaded into the upper end of the sleeve 75 2, a ball set 11 being inserted between the flange 9 and the cap 10. In the cap 10 is secured a telescopic feed screw mechanism 12 of ordinary construction. Extending longitudinally of the casing are three ratchet 80 levers 13, 14 and 15. The spindle ends 16, 17 and 18 of these levers form circular sleeves or straps which surround the toothed portion 5 of the spindle, the spindle forming a bearing or fulcrum for the oscillation of 85 the levers. At the other end of the casing are three cylinders 19, 20 and 21, whose axes are set at right angles to the length of the casing and at right angles to the longitudinal axis of the spindle. Reciprocating 90 in the cylinders are pistons 22, 23 and 24, each of which consists of a piston element 25 and a connecting rod element 26 which is in the form of a pin rigidly secured in the inner side of the piston element and 95 having a longitudinal slot 27 in its outer end into which projects a knob 28 on the end of the lever which is actuated by this particular piston, this knob being free to slide in the slot 27 to allow for the longitudinal movement due to the oscillation of the levers. The three cylinders 19, 20 and 21 are not set on the same line with respect to the spindle but the inner cylinder 20 is set nearer the spindle and somewhat between the other two so that the cylinder overlaps to a certain extent on the line of the spindle axis, enabling the end of the

100

105

casing to be of considerably less height than if the cylinders were all on the same line. This arrangement of the cylinders also has the advantage that the spindle ends of the 5 levers can be close together and yet the cylinder ends of the upper and lower levers need not be at any considerable angle from the spindle axis. Since by this arrangement of the cylinders the central lever 14 must be 10 of less length than the upper and lower levers 13 and 15, and consequently the piston 23 must have a shorter reciprocation in order to oscillate the lever 14 through the same angular distance as the levers 13 and 15, the cylinder 20 and the piston 23 are of 15 larger diameter than the cylinders 19 and 21 and the pistons 22 and 24, so that the piston 23 shall exert the same force on the lever 14 as the pistons 22 and 24. To limit and 20 equalize the angular movement of the levers 13, 14 and 15 a crank 29 is provided between the cylinders and the spindle. The casing 1 is split diagonally on the axis of this crank 29 semi-cylindrical bearing seats 30 25 being thus provided in each section of the casing for the ends of the crank 29 in which are placed ball bearing sets 31 surrounding the ends of the crank. The crank 29 has three offset portions 32, 33 and 34, one for 30 each ratchet lever, set at angles of 120° from each other, these offset portions journaling in split bearing boxes 35 sliding longitudinally in slots 36 in the ratchet levers. This crank mechanism controls and equalizes the 35 amount of angular movement of the levers causing each one to oscillate successively through the same angle of rotation with respect to the spindle. In the levers 13, 14 and 15 contiguous to the spindle 3 are set 40 respectively pawls 37, 38 and 39. These pawls 37, 38 and 39 are not set in their respective levers in the same position with respect to the longitudinal axes of their levers but are so set that each one of the series 45 from top to bottom will successively engage the same tooth of the spindle. This is accomplished by having the pawl in each lever from the top to the bottom successively advanced over the preceding pawl with respect to the longitudinal axes of the levers 50 an angular amount equal to the angular space occupied by one spindle tooth divided by the number of levers. The reciprocation of the pistons is accomplished by air admitted through an inlet passage 40 and 55 controlled by a rotary valve 41 which is operated through a pinion 42 on the upper end of the crank 29, an intermediate gear 43 and a gear 44 mounted on the rotary 60 valve 41.

The operation of the drill will be evident from the above description. The cylinders 19 and 20 and 21 are successively supplied with air and exhausted by the valve 41. The provision of the crank connecting the various levers allows the regulation and control of the respective positions of the levers and limits and equalizes their angular movement, as well as furnishing positive mechanical control of the valve 41. 70

It is to be understood that while the present showing and description disclose only one specific embodiment of the present invention, other forms and modifications are included within the spirit and scope thereof, 75 as expressed in the appended claims.

What I claim is:

1. In a close corner drill, a spindle, a plurality of cylinders mounted at right angles to the axis of said spindle, pistons in 80 said cylinders, ratchet levers engaging said spindle and directly connected to said pistons and a crank mechanism for equalizing and limiting the oscillation of said levers. 85

2. In a close corner drill, a spindle, a series of cylinders mounted at right angles to the axis of said spindle, one of said cylinders being at a less distance from the spindle than another and said cylinders having 90 areas inversely proportional to their distances from said spindle, pistons in said cylinders, driving levers for said spindle oscillated by said pinions and a crank mechanism for equalizing the angular movement of said levers. 95

3. In a close corner drill, a spindle, a plurality of cylinders mounted at right angles to the axis of said spindle, one of said cylinders being at a less distance from the 100 spindle than the others and one of said cylinders overlapping the others, pistons in said cylinders, driving levers for said spindle oscillated by said pistons and a crank mechanism for equalizing the angular movement of said levers. 105

4. In a close corner drill, a spindle, three cylinders mounted at right angles to the axis of said spindle, one of said cylinders being at a less distance from the spindle than the others and said cylinders having areas inversely proportional to their distances from said spindle, one of said cylinders overlapping the others, pistons in said cylinders, driving levers for said spindle oscillated by said pistons and a crank mechanism for equalizing the angular movement of said levers. 110 115

In testimony whereof, I have hereunto set my hand.

FRANCIS A. JIMERSON.
